EYELET ROW TAPING MACHINE

Raymond J. Holmes, Lynn, Mass.

Application January 5, 1933, Serial No. 650,288

41 Claims.

(CL 12—51)

In its broad aspects, the present invention relates to machines which are used in the manufacture of shoes to apply a reinforcing strip to a shoe upper part comprising either a sheet of pliable material or the quarters joined by a back seam. More specifically, the present invention relates to machines which are used to apply tape to that portion of the flesh face of a shoe upper part which is to be provided with a row of holes each forming or receiving one element of a closure. In some shoes the holes receive buttons, in others hooks, and in others eyelets. In the shoe industry the area in which the row of holes is to be formed and which is to be taped prior to the hole forming operation is called the button row, the hook row or the eyelet row, depending upon the type of closure with which the shoe is to be provided. For convenience the phrase "eyelet row" is used herein to designate the taped area irrespective of the ultimate use of the row of holes to be formed therein.

Usually the eyelet row is covered by a piece of tape placed alongside but without the plies of the folded margin of the shoe upper part. Usually the folded margin has a bent run extending along at least one end of the eyelet row. It has been proposed heretofore to provide these tape-applying machines with devices for permitting the work to be swung laterally by the operator during the tape-applying operation in order that the tape may be applied on a curved line along the bent run of the folded margin forming the termination of at least one end of the eyelet row.

One of the principal objects of the present invention is to produce a tape-applying machine which will shape at least one edge of the reinforcing stay so that it will fit the bent end on at least one end of the eyelet row.

Another of the principal objects of the present invention is to produce a tape-applying machine which will apply uniformly to successive work pieces a predetermined length of tape.

To the accomplishment of these objects, and such others as may appear hereinafter, the various features of the present invention reside in certain devices, combinations and arrangements of parts hereinafter described and then pointed out broadly and in detail in the appended claims, possessing advantages readily apparent to those skilled in the art.

The various features of the present invention will be readily understood from an inspection of the accompanying drawings illustrating the best

form of the invention at present known to the inventor, in which,

Figure 1 is a detail view in left side elevation of the tape-applying machine, the tape-severing knife and the tape-guide being shown in the positions they occupy during the tape-severing operation;

Fig. 2 is a detail view in front elevation;

Fig. 3 is a detail view in perspective of the tape showing its leading and trailing edges preformed;

Fig. 4 is a detail view in underside plan of the taped eyelet row;

Fig. 5 is a detail view in left side elevation, the tape-severing knife and the tape-guide being shown in the positions they occupy during the application of the tape to the work;

Fig. 6 is a detail view in right side sectional elevation taken substantially on the line 6—6, Fig. 2;

Fig. 7 is a detail view in vertical sectional elevation;

Fig. 8 is a detail view in perspective of the die for cutting a polyhedron out of the tape;

Fig. 9 is a detail view in sectional plan substantially on the line 9—9, Fig. 1;

Fig. 10 is a detail view in sectional plan substantially on the line 10—10, Fig. 1;

Fig. 11 is a detail view in perspective of the tape-severing knife and its supporting lever, and

Fig. 12 is a detail view in right side elevation, partly in section, of the tape-guide and the tape-severing knife.

Referring now to Fig. 4 the pliable material to which the reinforcing strip is to be applied is shown as a shoe upper part 14 provided with a folded margin 15. That portion of the flesh face of the shoe upper part 14, which is the face exposed to view in Fig. 4, and through which a row of holes is to be formed to receive buttons, hooks or eyelets, is called herein the eyelet row. As shown in Fig. 4 the eyelet row is covered by a piece of tape 16 placed alongside but without the plies of the folded margin. The folded margin 15 has a straight run 17 along one side of the eyelet row, a bent run 18 along one end of the eyelet row, and a bent run 19 along the other end of the eyelet run. The tape 16 is applied to the eyelet row with one longitudinal edge 20, engaged with the straight run 17, and with shaped ends 21 and 22, engaged, respectively, with the bent runs 18 and 19.

The machine herein shown for applying tape 16 to the eyelet row (Fig. 4) is similar in many respects to the taping machine illustrated in the patent to Osgood, 1,549,376, August 11, 1925.

The applying of the tape 16 to the eyelet row is accomplished by the combined action of the roll work support 23 (Figs. 1, 2 and 5) and a pressing member 24. The pressing member 24 is secured to a head member 25, or lever, which has a vertical movement and also an oscillating movement. The oscillating head 25 is mounted on the main frame 26 of the machine and it receives its oscillating movement from an eccentric 5 (not shown) on a driving shaft 27 carried by the main frame. The head 25 is provided with a slot 28 (Fig. 1) through which extends a stud fast on the main frame 26, said stud having a block 29 (Figs. 1 and 9) which is slidably mounted in the slot 28 and is journaled on the stud.

As the shaft 27 is rotated the eccentric thereon gives the head 25 an up and down movement and also a rocking movement, said movements causing the face of the pressing member 24 to move 10 toward and from the work on the work support and also to having a rocking or rolling contact with the work.

The work is guided into the machine by a guide 30 arranged to engage the external edge of the shoe part 14 which is parallel to the straight run 20. The tape is guided to the work by a tape-guide 31.

The tape is coiled in a roll (not shown) constituting the source of supply. From the coil the tape passes through an eye 32, (Figs. 1 and 2) and then under a flanged drum or roll 33, the milled surface of which engages the sticky face of the tape.

The drum 33 is loosely mounted on a stud 34 which is screwed into the head 25. One face of the drum 33 is provided with a ratchet 35 which is held from movement in a clock-wise direction by a spring-pressed pawl 36. From the drum 33 the tape passes over a take-up roll or feeler 37 35 which engages the tape on its nontacky face. The take-up is loosely mounted on a stud projecting laterally from an arm 38 (Fig. 1) loosely mounted on a stud 39 projecting laterally from a bracket 40 (Figs. 2 and 9) bolted to the left-side vertical face of the frame 26. From the roll 37 the tape passes under a roll 41 free to rotate 40 on the stud 39.

From the roll 41 the tape passes over a drum 42 (Figs. 1, 5 and 7). As shown in Fig. 7 the periphery of the drum 42 is provided with flanges 43 which embrace the tape, the peripheral surface of the drum between the flanges being provided with sharp projections 44 which bite into the tape and thus cause the drum 42 to rotate as the tape 50 is drawn out of the tape-guide 31 by the tape-applying instrumentalities. The drum 42 is provided with a hub 45 which rotates loosely on a stub shaft 46 projecting laterally from a bracket 47 (Figs. 2 and 7) projecting to the left from the machine frame 26 above the bracket 40. The drum 42 is prevented from rotating backwardly by a spring-pressed pivoted pawl 48 carried by a bracket 49 secured to the bracket 47. The pawl 48 engages a circular series of teeth 50 formed on the right-hand side of the drum 42.

From the drum 42 the tape passes over a flanged idler 51 (Fig. 1) journaled on a stud 52 projecting laterally from an ear 53 formed on a plate 54. The plate 54 is secured to a block 55 (Fig. 9) an extension of which is secured to the bottom of the bracket 40. From the idler 51 the tape passes under a flanged idler 56 journaled on a stud 57 projecting laterally from the downward and forward extension of the plate 54. From the idler 56 the tape passes over a flanged idler 58 jour-

naled on a stud 59 projecting laterally from a plate 60. The plate 60 is provided with a longitudinal slot 61 so that the plate 60 may be secured by two screws 62 adjustably to the downward and forward extension of the plate 54.

From the idler 58 the tape passes to the tape-guide 31. The bottom of the tape-guide 31 comprises a curved plate 63 (Fig. 12) the opposite longitudinal edges of which are bent upwardly to form a channel through which the tape passes. The channel plate 63 is provided with ears 64 which are received loosely by a stud 65 (Figs. 10 and 12) projecting through a plate 66 (Fig. 1) which depends from a block supported from the bracket 40. The tape-guide plate 63 is provided also with ears 67 (Fig. 12) to which is trunnioned centrally a tension device 68 having at one end a jaw to engage the tape and press it yieldingly against the plate 63 and having at its other end a tail to facilitate the elevation of the jaw from the tape by the operative. The tape-guide 31 is rotatable on the stud 65 but is held from movement longitudinally thereon by a latch 69, pivotally mounted on one side of the plate 63, the free end of which engages a peripheral groove 70 (Fig. 2) in the stud 65.

From the construction described it is apparent, as the drum 33 is free to rotate in a contra-clockwise direction viewing Fig. 1, that during the feed of the work over the work support 23 by the pressing member 24 there is a tendency for the pressing member to pull tape from the source of supply at each feeding step. But as the tacky face of the tape in the source of supply is stuck somewhat to the non-tacky face in an adjacent convolution, considerable force is required to unwind the tape. It is, therefore, undesirable to rely upon the pressing member 24 to pull tape from the source of supply as the pulling force exerted thereby would drum-head the tape between the work and the tape-guide 31 and thus interfere with the application of the tape to the work.

In the illustrated embodiment of the present invention the roll 33 is rotated in a manner presently to be described to unwind the tape from the coil in the source of supply and to produce an auxiliary supply of slack tape which is used up as needed by the pressing member 24. The take-up engages the slack tape under the mild tension of a coiled spring 71 (Figs. 1 and 2) one end of which is secured to a pin on the arm 38 and the other end of which is secured to a bracket 72 on the main frame located between the brackets 40 and 47. Movement of the take-up 37 under the influence of the spring 71 is limited by a screw adjustably secured to the bracket 72 as disclosed more fully in the patent to Osgood, No. 1,899,051, February 28, 1933.

As the pull-off 33 is mounted on the head 25 the pull-off ratchet 35 moves in an orbital path during the vertical reciprocation and lateral oscillating of the presser member 24. In order to rotate the pull-off 33 during these movements of the presser member the stud 39 loosely carries a pawl 73 (Fig. 1). The hubs of the arm 38 and the pawl 73 interfit beneath the idler 41, there being a space between the hubs to allow the take-up 37 and the pawl 73 to move relatively. Coiled about the hubs of the arm 38 and the pawl 73 is a spring 74 one end of which engages the arm 38 and the other end of which engages the pawl 73.

Fig. 1, in construction lines, shows the pawl 73 withdrawn from the orbital path of the ratchet 35. This is due to the position of the take-up 75

or feeler 37 which is held in engagement with the loop of withdrawn tape by the light spring 11. In consequence no tape is pulled from the source of supply by the roll 33 which is stationary during the operation of the tape-applying member 24. As the slack in the loop of withdrawn tape engaged by the take-up 37 is used up by the pressing member 24, the take-up 37 is moved by the tape against the light tension 10 of the spring 11 carrying the pawl 73 into the orbital path of the ratchet 35, as shown in full lines Fig. 1, when the pawl engages a tooth on the ratchet 35. Then as the ratchet 35 continues to move downwardly and laterally the pawl 73 rotates the ratchet 35 and the roll 33 to draw tape from the coil in the source of supply. During the movement of the ratchet 35 in engagement with the pawl 73 the spring 74 enables the pawl 73 to yield relatively to the take-up 37. 20 Thus, rotation of the pull-off 33 does not increase the tension of the take-up 37 on the tape engaged thereby.

In order to prevent the ratchet 35 from riding over the pawl 73 during the movement of the head 25, a bracket 75 is provided which carries an adjustable screw 76 for limiting the movement of the pawl 73 into the orbital path of the ratchet 35. In order to control the pull-off stroke of the pull-off 33 the pawl 73 is made in two parts 77 and 78 so that they may be adjusted longitudinally through the screw and slot connection 79. The selected adjusted position of the parts 77 and 78 is maintained by a drift 80, herein shown as a wedge block, interposed between the head of the pawl 73 and one end of the part 78.

In the illustrated embodiment of the invention the stroke of the pull-off 33 is such that more tape is pulled from the coil in the source of supply in a single stroke thereof than is used up by the pressing member 24 in a single feeding step thereof. With such a construction and mode of operation the withdrawn tape is bound to accumulate. But as the spring 71 maintains the take-up 37 engaged with the withdrawn tape during its accumulation, the pawl 73 is withdrawn from the orbital path of the ratchet 35 and the operation of the pull-off 33 suspended. When the pressing member 24 eats into the accumulation of withdrawn tape the pawl 73 is replaced in the orbital path of the ratchet 35 and the pull-off 33 is rotated again to withdraw more tape. In the preferred mode of operation the pull-off 33 operates in timed relation with the pressing member 24 during successive cycles varying in number depending upon prevailing conditions and then the operation of the pull-off 33 is suspended for one cycle, or, it may be, successive cycles, depending again on the prevailing conditions. Thus, while the pressing member 24 is operated periodically, the pull-off 33 is operated non-periodically.

When no work is in the machine the tape-guide 31 stands in the position shown in Fig. 1. 65 During the application of the tape to the work the tape-guide 31 stands in the position shown in Fig. 5. In order to rotate the tape-guide 31 on the stud 65 to transfer it from the position of Fig. 1 to that of Fig. 5 and to lock it in operating position the left-hand side of the flanged tape-guide plate 63 is provided with a hole which engages a pin 82 (Figs. 10 and 12) projecting laterally from a lever 83 (Figs. 10 and 12) pivoted on the stud 65. The front end of the lever 83 70 is secured rigidly to one end of a lever 84 (Figs.

1 and 10) pivoted on the stud 65, there being a distance piece 85 on the stud interposed between the lever 84 and the plate 66. The other end of the lever 84 is connected by a heavy coiled spring 86 (Figs. 1 and 2) to a bracket 87 secured to the plate 54. Thus, the spring 86 tends normally to hold the tape-guide 31 elevated in the position of Fig. 1.

The rear end of the lever 83 is pivoted to the bottom of a link 88 (Figs. 1, 5, 10 and 12) the upper end of which is provided with a slot 89 (Figs. 1 and 9) the sides of which embrace the shank of a screw 90 projecting laterally from one end of an arm 91. The arm 91 is secured to one end of a rock-shaft 92 journaled in the frame, a distance piece 93 being interposed, on the rock-shaft 92, between the frame 26 and the arm 91. The other end of the rock-shaft 92 is provided with an arm 94 (Figs. 2, 6 and 9) which is pivoted to the upper end of a plate 95. The lower end of the plate 95 is pivotally connected to a bar 96 which is carried by one end of a lever 97 centrally pivoted on the machine frame. The other end of the lever 97 is provided with an inclined slot 98 the walls of which embrace a cylindrical block 99 (Fig. 9) carried by the bent end 100 (Fig. 2) of a rock-shaft 101. The rock-shaft 101 is provided with an arm 102 suitably connected for control by the operative to a treadle-rod 103.

Downward movement of the treadle-rod 103 through the connections described, rotates the rock-shaft 92 in a contra-clockwise direction (Figs. 1 and 5), depresses the link 88 and rotates the tape-guide 31 on the stud 65 from the position of Fig. 1 to that of Fig. 5. In order to lock the tape-guide in operating position the link 88 is provided with a block 104 (Figs. 1 and 5) which, when the tape-guide 31 is in the position of Fig. 1, engages a rear edge on the vertical arm of a bell-crank lever 105 pivoted on the plate 54. The vertical arm of the bell-crank lever 105 is pressed into engagement with the end of the block 104 by a coiled spring 106 interposed between the arm and a block 107 secured to the plate 54. The lower end of the arm is provided with a shoulder 108 which, when the block 104 is carried downwardly by the link 88 under the influence of the treadle, engages over the upper forward corner of the block 104 and latches the tape-guide 31 in its operating position against the tension of the spring 86. The slot 89 allows the operative to release the treadle as soon as the tape-guide 31 is locked in its tape-applying position.

As indicated in Figs. 1 and 5 the machine is provided with a knife 109 for severing the tape at a point between the work and the delivery end of the tape-guide 31 when it is in the position of Fig. 1. The knife comprises a curved plate 110 (Fig. 11) having a front serrated cutting edge 111. The rear edge of the plate 110 is secured to a bar 112 which is carried by a clamp-block 113. The block 113 is secured to the vertical arm of a bell-crank lever 114 pivoted on the plate 66. The horizontal arm of the bell-crank lever 114 has a cam upper surface 115 which, when the parts are in the position of Fig. 1, is engaged by a button 116 (Figs. 1, 5, 9 and 12) rotatably mounted on one end of a horizontal rod 117 slidably mounted in the head 25. With this construction, when the parts are in the position of Fig. 1, movement of the head 25 to actuate the presser member 24 causes the button 116 to wipe along the cam surface 115 and thus operate the knife to sever the tape. The knife 109 is returned to its inoperative position, when the button 116 75

is elevated by the head 25 away from the cam surface 115, by a coiled spring 118 (Fig. 12) one end of which is connected to the plate 66 and the other end of which is connected to an eye formed 5 on the bell-crank lever 114, the plate 66 being provided with a pin 119 (Fig. 12) to limit the movement of the knife 103 under the influence of the spring 118.

When the parts are in the position of Fig. 5 10 the button 116 is held in a position clearing the cam surface 115, during the reciprocating and oscillating movement of the head 25, by a leaf spring 120 (Fig. 9) one end of which is secured to the head 25 and the other end of which presses 15 against the free end of the rod 117.

When the parts are in the position of Fig. 1 20 the button 116 is forced to the right and directly over the cam surface 115 by a cam 121 (Fig. 9) formed on one end of a bell-crank lever 122 (Figs. 20 1 and 5) pivoted on the plate 66. The lower end of the bell-crank lever 122 is embraced by pins 123 and 124 on the lower end of the link 88, the bell-crank lever being held in engagement with the pins by a coiled spring 125 one end of which 25 is secured to the plate 66 and the other end of which is secured to a bent plate 126 pinned to the bell-crank lever 122.

With this construction, when the link 88 is depressed to lower the tape-guide 31 into operative 30 position and to lock it in that position, the cam 121 is withdrawn from the button 116 thus to maintain the tape-severing knife inoperative during the tape-applying operation. When the link 88 is restored to the influence of the heavy spring 35 66 the tape-guide is elevated, the cam 121 pushes the button 116 in position over the cam surface 115, and the knife is actuated to sever the tape upon the next downward movement of the head 25.

40 The latch 108 which holds the parts in the position of Fig. 5 may be released, to permit the spring 86 to retract the tape-guide into the position of Fig. 1 and throw the knife into operation to sever the tape, by any suitable devices under 45 the control of the operative. To relieve the operative of the additional manipulations and to insure uniformity in the lengths of tape applied successively to similar work pieces, it is preferred, however, to control the latch automatically. In order that a predetermined length of tape 50 may be applied to the work, devices are provided for determining the extent to which the tape may be drawn through the tape-guide preparatory to the operation of the tape-severing cutter. Preferably these devices are connected with the latch 108 so that their movement, when the proper 55 amount of tape is drawn through the tape-guide, trips the latch and thus throws the actuating mechanism for the tape-severing knife into operation. The devices are thus rendered active at the proper time without any attention on the 60 part of the operative.

As shown in Figs. 1, 5 and 7 the tape is led towards the tape-guide 31 over the drum 42 which 65 is mounted to turn freely on the stud 46 and also upon the periphery of a controlling or measuring wheel 127 rotatably mounted on a sleeve 128 carried by the stud 46. The measuring wheel carries a clamping jaw or tooth 129 mounted to engage 70 one of a series of teeth 130 formed on the left-hand side face of the drum 42 and thus clamp the drum 42 and the measuring wheel 127 together so that they may rotate in unison as the tape is drawn towards the tape-guide 31 by the 75 tape-applying instrumentalities. The tooth 129

is formed on one end of a link 131 mounted to slide loosely through a block 132 secured to the measuring wheel 127. The other end of the link 131 rides in a slot 134 formed in the upper end of a lever 135. The link 131 carries a lateral pin 136 the opposite ends of which are provided with nuts 137 engaged with the lever 135. The lever 135 is pivoted on a pin 138 bridging the space between a pair of ears 139 formed on the block 132. The tooth 129 is pressed into engagement 10 with one of the series of teeth 130 by a spring 140 coiled about the link 131 and interposed between the block 132 and a collar 141 on the link 131.

In order to withdraw the tooth 129 from the 15 drum 42 the lower end of the lever 135 is engaged by one end of a screw 142 carried adjustably by one end of a long lever 143. Intermediate its ends the lever 143 is pivoted on a vertical pin 144 (Fig. 2) bridging the space between the ears 145 20 of a block 146 secured to the upper edge of the plate 54. The other end of the lever 143 is provided with a roll 147 (Figs. 1, 2 and 5) which is held by a coiled spring 148 (Fig. 2) interposed between the lever 143 and the block 146, in engagement 25 with a cam plate 149 carried by the link 88.

When the parts are in the position of Fig. 1 the cam plate 149 presses the roll 147 in a direction to cause the lever 143 to withdraw the clamping jaw 129 from engagement with the drum 42. 30 When the treadle-rod 103 is depressed by the operative to lower the link 88, the roll 147 rolls down the incline on the cam plate 149 thus releasing the lever 135 so that the spring 140 may press the clamping jaw 129 into engagement with the 35 drum 42. Thus during the tape-applying operation, the drawing of the tape through the tape-guide 31 causes the drum 42 and the measuring wheel 127 to move together as a unit. During this movement a spring 150 (Fig. 7), having one end 40 connected to a support 151 pinned to the stationary stud 46, and having its other end connected to a rod 152 projecting laterally from the measuring wheel 127, is wound up so that the measuring wheel 127 may be returned to its original 45 position when the clamping jaw 129 is disengaged from the drum 42. The original position of the measuring wheel 127 is determined by a stop 153 (Figs. 1 and 5) carried by the upper edge of the plate 54 and arranged to engage the 50 block 132.

The movement of the measuring wheel 127 under the influence of the tape is limited by a stop 154 (Fig. 7) having a knurled and slotted head 155 and a threaded shank 156. The shank 156 is provided with a washer 157 which is interposed between the stop 154 and a plate 158 rotatably mounted on the stud 46. The shank 156 passes through the plate 158, a circular slot 159 (Fig. 5) formed in the measuring wheel 127, and a plate 60 160 rotatably mounted on the sleeve 128. The threaded end of the shank 156 is provided with a nut 161. With this construction the position of the stop 154 with relation to the measuring wheel 127 may be varied within the limits defined by 65 the ends of the slot 159 and the adjusted position of the stop 154 may be retained by manipulating the knurled head 155 to clamp the measuring wheel 127 and the plates 158 and 160 together.

During the tape-applying operation, the drum 70 42 and the measuring wheel 127 rotate in unison in a clockwise direction (Fig. 5) until the stop 154 engages under the hooked end 1620 on the upper end of the bell-crank lever 105. When this occurs the latch 108 is withdrawn from the block 75

104 thus releasing the link 88 to the influence of the spring 86. As the link 88 rises, the cam plate 149, through the connections described, withdraws the clamping jaw 129 from the drum 42 thus restoring the measuring wheel 127 to the influence of the spring 150 which rotates the measuring wheel 121 in a contra-clockwise direction until the block 132 engages the stop 153.

It will be apparent to those skilled in the art that various features of the illustrated embodiment of the present invention, relating to the cutting out of a predetermined length of tape from the continuous length of tape leading from the source of supply so far described, are equally well suited to taping machines for applying a reinforcing strip to pliable shoe part material and to combine seam-pressing and taping machines for applying a reinforcing strip to the seam-ridge, formed by joining the quarters of a shoe upper, prior, during, or subsequent to the seam-ridge pressing operation.

In order to apply the tape 16 (Fig. 4) in a straight run to the eyelet row it is necessary to shape the leading and trailing edges 21 and 22 of the strip 16 so that they fit, respectively, the bent runs 18 and 19 of the folded margin 15. To this end the machine is provided with a die 162 (Fig. 8). This die is composed of two cutting edges 163 and 164 formed, respectively, on two plates 165 and 166 secured to a block 167 mounted to slide on the block 155 (Fig. 9). As shown in Fig. 8 the plates 165 and 166 meet in a miter joint. Thus the cutting edges of the die cut from the tape a polyhedron, specifically, a triangular prism, forming in the body portion of the tape adjacent one longitudinal edge thereof a reentrant angle, the vertex 167 (Fig. 3) of which is located between the longitudinal edges of the tape.

Referring to Fig. 4 the bends 18 and 19 of the margin 15 each comprise two straight runs formed by the snipping knife of the folding machine. In consequence the die 162 is shaped to make two straight converging cuts in the tape forming a dihedral angle therein having the vertex or dihedral angle edge 167. In other types of eyelet rows the bends in the folded margin may be curved. In such cases the angle between the cutting edges of the die 162 will be curvilinear. The vertex of this curvilinear angle will bear the same relationship to the longitudinal edges of the tape as the dihedral angle edge 167.

The die 162 operates in a way formed between two cutting blocks 168 and 169 having, with relation to the cutting edges 163 and 164, internal and external shearing edges 170 and 171, respectively. The internal shearing edge block 168 is formed on a base 172 (Figs. 8 and 9) secured to the block 155. The external shearing edge block 169 is secured to the base 172. As indicated in Figs. 2 and 9 the tape is led over the shearing edge blocks 168 and 169 beneath a forked stripper plate 173 secured to the block 169.

In order to actuate the die 162, the block 166 is secured to one end of a plunger 174 (Fig. 9) mounted to slide in a cylinder 175 carried by a plate 176 secured to the block 155. The die 162 is normally held in an inoperative position by a spring 177 coiled about the cylinder 175 and interposed between the plate 176 and a collar 178 secured to the plunger 174. The free end of the plunger 174 is engaged by one end of a lever 179 pivotally mounted on a vertical pin 180 carried by a yoke-block 181 secured to the plate 176. The rear end of the lever 179 is connected rigidly to one end of a rod 182 the other end of which

is provided with a roll 183 engaged with a cam plate 184 secured to the plate 95.

With this construction when the treadle-rod 103 is depressed by the operative to position the tape-guide 31 for the tape-applying operation, to lock the tape-guide in its tape-applying position, and to throw the tape-severing knife 109 out of operation, the plate 95 is elevated, as indicated in Fig. 6, thus causing the lever 179 to operate the plunger 174 and force the die through the 10 tape.

As the die operates on the sticky face of the tape the polyhedron cut out of the tape sticks to the cutting edges of the die 162 and is retained in the angle between the plates 165 and 166. 15 When the die is actuated again to cut another polyhedron out of the tape the uncoated face of the polyhedron previously cut out is stuck to the sticky face of the polyhedron being cut out so that they are both retained in the angle between 20 the plates 165 and 166. This action is repeated with the result that a stack of stuck together polyhedrons gradually forms in the angle between the plates 165 and 166 finally working out through an opening 185 (Figs. 2 and 8) from 25 which the stack may project for a considerable distance without danger of disintegrating.

In order to correlate the cuts made by the die 162 with the cross cut 186 (Fig. 3) made by the knife 109 so that the cut 186 will intersect the 30 vertex or dihedral angle edge 167 and thus shape both the leading and trailing edges 21 and 22 of the predetermined length of tape, the length of the tape in the machine extending from its leading edge 21 (Fig. 1) back to the line of junction between the cutting edges 163 and 164 should be a multiple of the predetermined length of tape to be applied to the work. This multiple distance, within limits, may be obtained or varied as desired by adjusting the position of the 40 plate 60, carrying the roll 59, through its slot and screw connection with the plate 54. For instance, if the predetermined length of tape to be applied to the work is to be one inch the length of tape extending from the leading edge 21 (Fig. 45 1) to the center of the die 162 may be six inches. If the predetermined length of tape to be applied to the work is to be one and one-half inches no adjustment of the plate is necessary. It would, however, be necessary to shift the position of 50 the stop 154 so that after a stretch of tape one and one-half inches long had been fed past the drum 42 the stop would engage under the hook 1620 and trip the latch 108.

To operate the machine the operative adjusts 55 the positions of the stop 154 and the plate 60 to accommodate the machine to the particular length of tape it is desired to apply to the eyelet row. The operative places the rear portion of the straight run 17 of the folded margin 15 60 against an overhanging shoulder 188 (Figs. 1, 2 and 5) on the gage 30. The bend 18 is located back of the shoulder 188 a distance such that when the operative depresses the treadle-rod 103 the tape-guide 31 will deposit, in moving into 65 the position of Fig. 5, the leading edge 21 into the angle formed between the eyelet row and the bend 18. Immediately after the treadle-rod 103 has been depressed it is released. In addition to lowering the tape-guide into its tape-applying 70 position the depression of the treadle-rod 103 actuates the die 162 to take a bite out of one edge of the tape, throws the tape-severing knife 109 out of operation, clutches the measuring wheel 127 to the drum 42, and operates the latch 108 75

to retain the tape-guide and the measuring wheel 127 in operation and the tape-severing knife out of operation. As soon as the leading edge of the tape is fitted into the bend 18 by the tape-guide 5 31 the continuously operating presser member 24 applies the tape progressively to the eyelet row and feeds the work in a direction away from the operative. During the feeding of the work the pressing member 24 draws tape from the slack 10 source of supply through the tape-guide 31 thus rotating the drum 42 and the measuring wheel 127. Just as the predetermined amount of tape has been drawn through the tape-guide 31 the stop 154 engages the hook 1620 and trips the 15 latch 108. Immediately the tape-guide 31 and the measuring wheel 127 fly back to their original positions and the tape-severing knife 109 is actuated to sever the tape. The pressing member 24 continues to operate until the trailing edge 20 22 formed by the successive action of the die 162 and the tape-severing knife 109 is fitted into the bend 22 and the taped eyelet row is fed beyond the influence of the pressing member 24.

As indicated in Figs. 1, 2 and 5 the illustrated embodiment of the present invention is provided with fingers 191 corresponding in function to the fingers 54 in the patent to Osgood, No. 1,549,376, August 11, 1925. When operating upon an eyelet row to be incorporated in a pump 25 or oxford the tape is applied in a straight path the fingers 191 acting merely as strippers. When operating upon an eyelet row to be incorporated in a high shoe, the fingers 191 permit the tape to be applied in a curved path intermediate the 30 ends of the eyelet row. It would not be necessary to apply the tape in a curved path around the bent ends of the eyelet row owing to the provision in the machine of means for preforming the leading and trailing edges of the tape.

Nothing herein explained is to be interpreted as limiting the various features of the present invention in the scope of its application to use 40 in connection with the particular machine or the particular mode of operation or both selected for purposes of illustration and explanation. While the particulars of construction herein set forth are well suited to one mechanical form of the invention and to the use to which it is put, it is not limited to this use, nor 45 to these details of construction, nor to the conjoint use of all its features, nor is it to be understood that these particulars are essential since they may be modified within the skill of the artisan without departing from the true scope 50 of the actual invention, characterizing features of which are set forth in the following claims by the intentional use of generic terms and expressions inclusive of various modifications.

What is claimed as new, is:

1. A tape-applying machine having, in combination, tape-applying mechanism, tape-severing mechanism, means under the control of the operative for throwing the tape-severing mechanism out of operation, and mechanism rendered active in throwing the severing mechanism out of operation for automatically throwing the severing mechanism into operation.

2. A tape-applying machine having, in combination, tape-applying mechanism, tape-severing mechanism, means under the control of the operative for throwing the tape-severing mechanism out of operation and for retaining it out of operation, and mechanism rendered active in throwing the severing mechanism out of oper-

ation for automatically throwing the severing mechanism into operation.

3. A tape-applying machine having, in combination, tape-applying mechanism, tape-severing mechanism, means under the control of the operative for throwing the tape-severing mechanism out of operation, latching means for retaining the tape-severing mechanism out of operation, and a tape-measuring mechanism for automatically disengaging the latching means. 10

4. A tape-applying machine having, in combination, tape-applying mechanism, a tape-severing knife, actuating mechanism adapted to be thrown into operation by the operative for throwing the knife out of operation, latching 15 means for retaining the actuating mechanism in action, and a tape-measuring mechanism rendered active by the actuating mechanism for disengaging the latching means.

5. A tape-applying machine having, in combination, a tape guide, mechanism for drawing tape through the tape guide and for applying the withdrawn tape to the work, a tape-severing device, and mechanism, including means engageable with the tape prior to the engagement 20 of the tape with the work, automatically thrown into operation upon the drawing of a predetermined length of tape through the tape-guide for actuating the device to sever the tape during the continued operation of the tape-applying 25 mechanism.

6. A tape-applying machine having, in combination, tape-applying mechanism, a tape-measurer operable prior to the engagement of the tape with the work for determining the 30 length of tape to be applied to the work, and a tape-severing device controlled by the operation of the tape-measurer to sever the tape.

7. A tape-applying machine having, in combination, tape-applying mechanism including 40 means for feeding tape thereto, tape-severing mechanism movable independently of the tape-applying mechanism, and means moving with the tape during its feed for throwing the tape-severing mechanism into operation. 45

8. A tape-applying machine having, in combination, tape-applying mechanism including means for feeding tape thereto, a drum rotatable by the tape during its feed, tape-severing mechanism, and means movable with the drum for throwing the tape-severing mechanism into operation. 50

9. A tape-applying machine having, in combination, tape-applying mechanism including means for feeding tape thereto, tape-severing 55 mechanism, a drum rotatable by the tape during its feed, a stop wheel movable with the drum for throwing the tape-severing mechanism into operation, and means under the control of the operative for throwing the severing mechanism 60 out of operation and for clutching the drum and the wheel together.

10. A reinforcing machine having, in combination, a support for a piece of sheet material having an eyelet row and a folded margin extending in a straight run along one longitudinal edge of the eyelet row and in a bent run around at least one end of the eyelet row, means for producing a stay having end edges and having one longitudinal edge shorter than the other, 70 and means for applying the stay to the eyelet row with the shorter longitudinal edge of the stay and one end edge thereof adjacent, respectively, the straight run and a bent run.

11. A reinforcing machine having, in combina-

tion, a support for a piece of sheet material having an eyelet row and a folded margin extending in a straight run along one longitudinal edge of the eyelet row and in runs bent in opposite directions around the ends, respectively, of the eyelet row, means for shaping the leading and trailing edges of a stay to fit, respectively, the bent ends of the eyelet row, and means for applying the stay to the eyelet row with one of the longitudinal edges of the stay and its opposite ends engaged, respectively, with the straight and bent runs.

12. In a tape-applying machine, the combination with means for progressively applying tape to an eyelet row the opposite ends of which are bent in different directions, of means for shaping the leading and trailing edges of the tape to fit, respectively, the bent ends of the eyelet row.

13. In a tape-applying machine, the combination with means for progressively applying the tape to the work, of means for cutting out of the tape at least one pentahedron in advance of the application of the tape to the work.

14. In a tape-applying machine, the combination with means for progressively applying a predetermined length of tape to the work, of means for forming at least one reentrant angle in the tape in advance of the application of said predetermined length to the work.

15. In a tape-applying machine, the combination with means for progressively applying the tape to the work, and means for forming at least one reentrant angle in the tape in advance of its application to the work, of means for severing the tape on a line extending from one longitudinal edge thereof to the vertex of the angle.

16. In a tape-applying machine, the combination with means for progressively applying the tape to the work, of means for providing the leading edge of the tape with three dihedral angles.

17. In a tape-applying machine, the combination with means for progressively applying the tape to the work and means for providing the leading edge of the tape with three dihedral angles, of means for providing the tape being applied to the work with a trailing edge having three dihedral angles.

18. In a tape-applying machine, the combination with means for progressively applying a predetermined length of tape to the work, of a die for cutting a pentahedron out of the tape in advance of the application of said predetermined length to the work.

19. In a tape-applying machine, the combination with means for progressively applying a predetermined length of tape to the work, of a die for cutting a triangular prism out of the tape in advance of the application of said predetermined length to the work.

20. In a tape-applying machine, the combination with means for progressively applying a predetermined length of tape to the work, of a die for forming in the body portion of the tape a dihedral angle edge intermediate the longitudinal edges of the tape in advance of the application of said predetermined length to the work.

21. In a tape-applying machine, the combination with means for progressively applying the tape to the work and a die for forming in the body portion of the tape a dihedral angle edge intermediate the longitudinal edges of the tape, of a knife for severing the tape on a line extending from one longitudinal edge thereof to the dihedral angle edge.

22. A tape-applying machine having, in com-

bination, mechanism for applying a predetermined length of tape to the work, means for conducting the tape to the tape-applying mechanism including a cutting block over which the tape is drawn, and a die cooperating with the block for notching a portion of the tape other than said predetermined length along one longitudinal edge during the operation of the tape-applying mechanism.

23. A tape-applying machine having, in combination, mechanism for applying a predetermined length of tape to the work, means for conducting the tape to the tape-applying mechanism including a cutting block over which the non-tacky face of the tape is drawn, and a die comprising a pair of converging cutting edges forming an internal angle between them acting on the tacky face side of the tape and in cooperation with the block for notching a portion of the tape other than said predetermined length along one longitudinal edge during the operation of the tape-applying mechanism.

24. A tape-applying machine having, in combination, tape-applying mechanism, means for conducting the tape to the tape-applying mechanism including a cutting block over which the non-tacky face of the tape is drawn, and a die comprising a pair of converging cutting edges forming an internal angle between them acting on the tacky face side of the tape and in cooperation with the block for notching the tape along one longitudinal edge, there being an opening leading to the internal angle out of which the pieces died out of the tape may pass in a stack.

25. In a tape-applying machine, the combination with a die for notching the tape along one longitudinal edge, and a knife for severing the tape, of means for operating the die and the knife successively.

26. In a tape-applying machine, the combination with a die for notching the tape along one longitudinal edge, a knife for severing the tape, and means for operating the die and the knife successively, of means for correlating at least one notch with at least one severing cut.

27. A reinforcing machine having, in combination, a support for a piece of sheet material having an eyelet row and a folded margin extending in a bent run around at least one end of the eyelet row, means for producing a stay having end edges and having one longitudinal edge shorter than the other, and means for applying the stay to the eyelet row with one of the end edges of the stay engaged with a bent run.

28. A tape-applying machine having, in combination, a tape guide, mechanism for drawing tape through the tape guide and for applying the withdrawn tape to the work, a tape-severing device, means for setting the machine for the severance of a predetermined length of tape, and mechanism, including means engageable with the tape prior to the engagement of the tape with the work, for actuating the severing device to sever the tape, said mechanism being automatically thrown into operation upon the drawing of the predetermined length of tape through the tape guide.

29. A reinforcing machine having, in combination, a support for a piece of sheet material having an eyelet row and a folded margin extending in a straight run along one longitudinal edge of the eyelet row and in a bent run around at least one end of the eyelet row, means for gaging the

position of the sheet material on the support, means for providing at least one end of a stay with an edge conforming to the bent run, and means for applying the stay to the eyelet row with one of the longitudinal edges of the stay and said end edge engaged, respectively, with the straight and bent runs.

30. A reinforcing machine having, in combination, a support for a piece of sheet material having an eyelet row and a folded margin extending in a straight run along one longitudinal edge of the eyelet row and in bent runs around the ends, respectively, of the eyelet row, means for gaging the position of the sheet material on the support, means for providing the ends of a stay with edges conforming to the bent runs, respectively, and means for applying the stay to the eyelet row with one of the longitudinal edges of the stay and said end edges engaged, respectively, with the straight and bent runs.

31. A reinforcing machine having, in combination, a support for a piece of sheet material having an eyelet row and a folded margin extending in a bent run around at least one end of the eyelet row, means for gaging the position of the sheet material on the support, and means for applying a stay to the eyelet row with one of the end edges of the stay engaged with the bent run.

32. A tape-applying machine having, in combination, a tape-guide, mechanism for drawing the tape through the tape-guide and for applying the withdrawn tape to the work, a tape-severing device interposable between the tape-guide and the work, and mechanism automatically thrown into operation upon the drawing of a predetermined length of tape through the tape-guide for actuating the device to sever the tape.

33. A tape-applying machine having, in combination, a tape-guide, mechanism for drawing the tape through the tape-guide and for applying the withdrawn tape to the work, a tape-severing device interposable between the tape-guide and the tape drawing and applying mechanism, and mechanism automatically thrown into operation upon the drawing of a predetermined length of tape through the tape-guide for actuating the device to sever the tape.

34. In a tape-applying machine, the combination with means for progressively applying tape to an eyelet row the opposite ends of which are bent in opposite directions, of means for shaping the leading and trailing edges of the tape to fit, respectively, the bent ends of the eyelet row.

35. A tape-applying machine having, in combination, a tape-guide, mechanism for drawing the tape through the tape-guide and for applying the withdrawn tape to the work, a tape-severing device, in the path of operation of which the tape-guide normally lies, interposable between the tape-guide and the work, and mechanism automatically thrown into operation upon the drawing of a predetermined length of tape through the tape-guide for withdrawing the tape-guide

from the path of operation of the tape-severing device and for actuating the device to sever the tape.

36. A tape-applying machine having, in combination, a tape-guide, mechanism for drawing the tape through the tape-guide and for applying the withdrawn tape to the work, a tape-severing device, in the path of operation of which the tape-guide normally lies, interposable between the tape-guide and the tape drawing and applying mechanism, and mechanism automatically thrown into operation upon the drawing of a predetermined length of tape through the tape-guide for withdrawing the tape-guide from the path of operation of the tape-severing device and for actuating the device to sever the tape.

37. In a tape-applying machine, the combination with means for progressively applying a predetermined length of tape to an eyelet row the opposite ends of which are bent, and means for partially shaping successively the leading and trailing edges of said length of tape for fitting said bent ends, of means for completing the shaping of the leading edge after the partial shaping of the trailing edge.

38. In a tape-applying machine, the combination with means for progressively applying a predetermined length of tape to an eyelet row the opposite ends of which are bent in opposite directions, and means for partially shaping successively the leading and trailing edges of said length of tape for fitting said oppositely bent ends, of means for completing the shaping of the leading edge after the partial shaping of the trailing edge.

39. In a tape-applying machine, the combination with means for progressively applying the tape to the work, and means for cutting out of the tape at least one pentahedron in advance of the application of the tape to the work, of means for thereafter severing the tape across the portion thereof from which the pentahedron is cut.

40. In a tape-applying machine, the combination with means for progressively applying a predetermined length of tape to the work, and means for forming two spaced reentrant angles in the tape, one edge of each of said angles comprising an edge of the predetermined length of tape, of means for severing the tape intersectingly of the vertex of the first reentrant angle after the formation of both angles.

41. In a tape-applying machine, the combination with means for progressively applying a predetermined length of tape to the work, and means for forming a plurality of spaced reentrant angles in the tape, one edge of each angle in a successive pair of angles comprising an edge of the predetermined length of tape, of means for severing the tape intersectingly of the vertex of the first angle of a successive pair of angles after the formation of both angles of said successive pair.
